BURNER CONTROL MECHANISM

Richard Besocke, Arcadia, Calif., assignor of
eighty per cent to John P. Frank, Arcadia,
Calif.

Application February 11, 1941, Serial No. 378,351

14 Claims.

(Cl. 126—42)

This invention relates to stoves and ranges, or similar apparatus employing a burner that can be covered by a lid; and the general object of the invention is to prevent accidental turning on of the burner when the lid is down covering it. While the invention is described in the following specification, as applied to a gas-burning range or stove, it can as readily be applied to a range having electrically operated burners.

In constructions of this kind, the lid is usually hinged at the back of the stove, and a lock is provided for the control member that turns on the current to the burner, or opens the valve for supplying gas to a burner. Heretofore mechanism has been provided for preventing the closing movement of the lid if the control member, or control members for the burners, are not in the "off" position. Such a lid has considerable weight, and also gives a considerable leverage to the operator of the stove, so that in closing the lid, such control mechanism could readily be broken or injured. One of the objects of the present invention is to provide apparatus of this kind with means for preventing accidental injury to the apparatus if it is attempted to close the lid before all the burners have been turned off.

A further object of the invention is to provide burner control apparatus with means for yieldingly resisting the closing of the lid if the control means for the burner is not in the "off" position.

A further object of the invention is to provide apparatus of this kind, having means for normally locking the control member of the burner in its "off" position, and to provide automatic means for releasing this lock when the lid is raised. Also, to accomplish this in such a way that a delayed action occurs in the release of the lock, insuring that the lid must be substantially completely raised before the burner can be turned on.

The apparatus, in its preferred form, includes a contact member that is engaged by the lid in its closed position, and this contact member is provided with means for advancing it when the lid is raised. One of the objects of the invention is to provide a connection between this contact member and the lock that locks the control member against operation, operating in such a way that if the lid is closed while the control member is in its "on" position, the lock will be yieldingly pressed toward its locking position, and at the same time, this connection to the lock will operate in such a way as to interpose a stop

5 back of the contact member or in its path, so that a considerable resistance will be offered to the closing of the lid. In this way, a person closing the lid becomes apprised of the wrong position of the control member, and he can then move it to its closed position and complete the closing movement of the lid.

Further objects of the invention will appear hereinafter.

10 The invention consists in the novel parts and combination of parts to be described hereinafter, all of which contribute to produce an efficient burner control mechanism.

15 A preferred embodiment of the invention is described in the following specification, while the broad scope of the invention is pointed out in the appended claims.

In the drawings:

20 Fig. 1 is a perspective of a stove having lids provided with my control apparatus, and showing one of the lids in its closed position, and one of the lids in an open position, so as to expose a griddle having a burner under it.

25 Fig. 2 is a vertical section taken about in the plane of the line 2—2 of Fig. 1, passing through the upper part of the stove and showing the lid in its open position, and the control member for the burner in its closed position.

30 Fig. 3 is a fragmentary view, and is a perspective upon an enlarged scale of the burner valve and lock for the same. This view also shows a portion of the manifold supplying gas to the burner, and also a portion of the pull rod that connects the lock to the lid-controlled contact mechanism at the back of the stove.

35 Fig. 4 is a view similar to Fig. 2, but with certain parts broken away and showing a portion of the lid in a partially raised position. This view further illustrates the function of an automatic stop that is moved into the path of the contact member or resister, that resists the closing of the lid if the control member for the burner is in the "on" position, as illustrated in Fig. 4.

40 Fig. 5 is a sectional plan taken about on the line 5—5 of Fig. 4 and Fig. 7, and further illustrating the automatic stop that cooperates with the contact member, to resist its movement if the control member for the burner is in the "on" position.

45 Fig. 6 is a view similar to Fig. 4, but showing the contact member pushed back by the closed lid, the automatic stop having been withdrawn by reason of the fact that the control member for the burner is in its "off" position.

50 Fig. 7 is a rear elevation of the apparatus at

the back of the stove, and particularly illustrating the automatic stop that is projected automatically into the path of the contact member when the contact member is moved forward at the time the lid is raised.

Fig. 7a is a rear elevation of a cushion plate that cooperates with the contact member and the automatic stop, and which also guides the contact member.

Fig. 8 is a vertical section taken about on the line 8-8 of Fig. 7, and further illustrating the functioning of the automatic stop and the cushion plate for resisting the closing movement of the lid, if the control member for the burner is in its "on" position.

Fig. 9 is a vertical section taken at the rear and looking toward the front, and illustrating the automatic stop projected into the path of the contact member. This view illustrates the automatic stop lever in dotted lines in its withdrawn position, with the automatic stop out of operation.

Fig. 10 is a diagrammatic plan illustrating how the improvement may be applied to a gang of control members for a plurality of burners.

In the stove illustrated, the lid 1 is movably attached to the stove body 2 by a hinge 3. In Fig. 5 the parts are shown in their normal condition of rest, at which time the control member 4 for the burner 5 is in its "off" position—that is to say, the gas valve 6 is in its closed position, shutting off flow to the burner from a gas manifold 7.

In this normal condition also, the control member 4 is locked against operation. The lock 8 for accomplishing this is preferably in the form of a bracket or shoe 8 with two vertical extensions 9 and 10, the former of which has an opening or eye 11 that guides it to slide on the valve stem 12. The extension 10 has a socket or opening 13 or other means for locking the stem, and in the present instance the stem has a neck 14 having a cross-section to fit the socket. The socket may be of D-form, or of some angular shape that will cooperate with the neck and prevent it from turning.

The lock is moved automatically to its release position (shown in Fig. 3) by an actuating member 15 in the form of a pull-rod or link attached to it. The other end of this rod 15 is moved automatically when the lid is moved to its raised position.

When the lid is down, it is engaged by a resister or contact member or plunger 16 having a rounded nose that cams on the back edge of the lid or a leaf of the hinge, and this plunger 16 is guided to slide longitudinally in a frame plate 17. Some means, for example, a coil spring 18, holds the nose of the contact member against the lid.

In the closing movement of the lid, if the control member 4 is in its "off" position, a pin 19 in the plunger 16 can move back through a small notch 20 (see Fig. 7a) in a cushion-plate 21, that is to say, the backward movement of the plunger is unobstructed. But if the control member 4 is in its open position a stop 22 will lie projected into the path of the pin 19 and obstruct this movement.

The stop 22 is moved in automatically by connecting means that connects the plunger 16 to the lock 8. This connection includes a rigid arm 23 carried by the plunger with its outer end moving between two collars 24 and 25 fixed on the actuator or pull-rod 15 that is attached to

the lock 8. A lost motion effect is attained by reason of the fact that the end of the arm 23 is located a considerable distance back of the forward collar 25, and hence when the plunger 16 is moved forward when the lid is being raised, the lid will substantially be fully raised before the last part of the movement brings the arm against the collar 25. This shifts the locking shoe 8 to the right and releases it from the neck 14. The burner can now be turned on.

As the draw-rod 15 moves forward it throws the stop 22 into its active position as in Fig. 9. This is accomplished by a cam 27 attached to the draw-rod, and having a cone face 28 that normally rests against the edge of a lever 29 (see Fig. 6), to hold the lever back as indicated in dotted lines in Fig. 9. When the rod moves forward to unlock the control member 4, the cone face moves away and lets the lever be pulled over to its active position by its coiled spring 30.

The connection from the arm 23 to the rod 15 for moving the lock-shoe 8 in its locking direction, includes a spring 31. When the arm 23 is moved back it compresses this spring and builds up energy in it, and before the plunger 16 has moved back far enough for the pin 19 to strike the stop 22, the spring 31 will shift the draw-rod sufficiently to cause the cone face 28 to swing away the stop lever. The pin can then move all the way back into the notch 20 as in Fig. 6. This will happen, of course, if the control member 4 is in its "off" position so that the neck 14 permits the lock 8 to slide over it. If the control member 4 is in the "on" position for the burner, the spring 31 cannot shift the draw-rod 15, and in that case the stop 22 will not be withdrawn, and the cushion plate will stop the closing movement of the lid. This will be accomplished yieldingly because the cushion plate is guided to slide back on guide pins 32 so as to compress coil springs 33 mounted on the same.

This considerable resistance is a warning that the control members are not all in their "off" positions.

The burner 5 is illustrated as a single burner under a griddle 34, but, of course, these improvements can be applied to a gang of control members 35 as illustrated diagrammatically in Fig. 10. In such a construction a draw-rod 15a would be connected to a rigid cross-head 26 carrying individual pull rods 36 leading over to the different valves or control members. If desired, an attempt to close down the lid when the control members are in their "on" positions, may give an alarm by closing an electric circuit through a bell 37 through the agency of contacts 38 and 39, one of which is fixed and the other carried on the cushion-plate 21 (see Fig. 7).

The mode of operation will now be briefly restated.

In the position of rest of the parts, they have the relation indicated in Fig. 6, at which time the resister or contact member 16 is held in its extreme rear position by contact of its rounded nose with the edge of the closed lid, or with the leaf of the spring 3. At this time the stop pin 19 is located in the notch 20 in the cushion-plate 21, and the lock-shoe 8 is telescoped over the neck 14 on the stem 12 of the control member 4. When the lid is raised, the contact member or plunger 16 will be advanced by its spring 18, as indicated in Fig. 2, and when this occurs the arm 23 will move against the collar 25 on the draw-rod 15 and push the same forwardly. This removes the cone face 28 from contact with the

tail of the lever 29, whereupon the spring 30 of this lever will pull it toward the left as viewed in Fig. 9, so as to project the stop 22 into the path of the stop pin 19. In other words, this stop 22 covers up the notch 20. As the movement of the arm 23 is completed, the lock-shoe 8 will be slipped off of the neck 14, which releases the control member, enabling the burner to be turned on. Fig. 5 illustrates this stop 22 located back of the pin 19. The control member, when in its "off" position, inhibits the operation of the stop 22 so that there then will be no functioning of the yielding resistance springs 33 when the lid 1 is raised and lowered.

It will be evident that in this action, it is merely necessary to provide a stop to cooperate in some way with the plunger 16 to resist its being moved backwardly by the closing lid, unless permitted to do so freely by the control member 4 when in its "off" position.

Now, if it is attempted to close the lid while the control member 4 is in its "on" position, the pin 19 will come against the stop 22 and the member 16 will then resist the further movement of the lid by forcing the cushion-plate 21 back, compressing its springs 33. This resistance will indicate to the person attempting to close the lid, that the control members for the burners are not in their "off" position. This rearward movement of the plunger 16, of course, causes the arm 23 to move back and compress the spring 31. This, of course, will exert tension in the draw-rod 15, but will merely result in pressing the locking-shoe 8 against the end of the neck 14, but will not break any of the parts. Furthermore, it will not shift the collar 27 and the cone face 28 into alignment with the lever 29, and hence it will not release the contact member or plunger 16 from the stop 22. If the apparatus has the alarm buzzer or bell attachment 37, this buzzer or bell will ring to indicate to the operator of the stove, that he is doing something wrong. If the operator does commence to close the lid with the control member 4 in its "on" position, and he develops a resistance to closing the lid through the operation of the plunger 16, it will not be necessary for the lid to be raised. It will merely be necessary to move the handle of the control member to the "off" position, whereupon the spring 31 will pull the lock 8 onto the neck 14, which will incidentally move the collar 27 into a position to withdraw the stop 22 from the side of the plunger. In doing this it may be necessary to ease up slightly on the lid so that the pressure of the pin 19 against the stop 22 will not prevent the withdrawal of the stop.

Many other embodiments of the invention may be resorted to without departing from the spirit of the invention.

What I claim is:

1. In a stove, the combination of a burner, a hinged lid mounted to close down over the burner, a movable control member for turning on the burner, a movable resister mounted so as to be moved by the closing of the lid, a stop capable of movement into the path of the resister for limiting the relative movement thereof under the action of the closing lid, and means for yieldingly resisting the movement of the said stop and the resister when moved by the closing lid.

2. In a stove, the combination of a burner, a hinged lid mounted to close down over the burner, a movable control member for turning on the burner, a movable resister mounted so as to be

moved by the closing of the lid, a stop capable of movement into the path of the resister for limiting the relative movement thereof under the action of the closing lid, means for yieldingly resisting the movement of the said stop and the resister when moved by the closing lid, locking means for the control member for locking the same against actuation when the lid is down, and means for moving the locking means to its releasing position when the lid is moved to its raised position.

3. In a stove, the combination of a burner, a hinged lid mounted to close down over the burner, a movable control member for turning on the burner, a movable resister mounted so as to be moved by the closing of the lid, a stop capable of movement into the path of the resister for limiting the relative movement thereof under the action of the closing lid, means for yieldingly resisting the movement of the said stop and the resister when moved by the closing lid, said control member having a rotatable stem with a locking neck thereon, a locking shoe mounted to shift out of, or into, engagement with said neck to lock the burner against being turned on, and means for effecting a movement of said shoe when the lid is opened to release the said stem and permit the burner to be turned on.

4. In a stove, the combination of a burner, a movable control member having a rotatable stem for turning on the burner, said stem having a locking collar thereon, a shoe mounted to shift longitudinally of the stem for engaging the collar to prevent rotation of the stem, means brought into action by the closing movement of the lid for shifting the shoe into engagement with the collar to lock the stem against rotation, and including a yielding connection to prevent straining any of said parts if the burner is open and the collar in a position to prevent movement of the shoe into its locking relation with the collar.

5. In a stove, the combination of a burner, a movable control member having a rotatable stem for turning on the burner, said stem having a locking collar thereon, a shoe supported to slide on the stem and having a socket to engage over the collar to prevent rotation of the stem, means brought into action by the closing movement of the lid for shifting the shoe into engagement with the collar to lock the stem against rotation, and including a yielding connection to prevent straining any of said parts if the burner is open and the collar in a position to prevent movement of the shoe into its locking relation with the collar.

6. In a stove, the combination of a movable control member, a lid with a hinge connection supporting the same and capable of closing over the burner, a plunger with means for guiding the same to slide longitudinally, and engaging the lid adjacent the hinge when the lid is in its closed position, locking means for interlocking with the control member for locking the same against turning the burner on, and means including a resilient member between the plunger and the last-named means for yieldingly moving the interlocking means into a position to lock the control means against turning the burner on, when the lid is being moved to its closed position.

7. In a stove, the combination of a movable control member, a lid with a hinge connection supporting the same and capable of closing over the burner, a plunger with means for guiding the same to slide longitudinally, and engaging the lid adjacent the hinge when the lid is in its closed position, a spring for advancing the plung-

er when the lid is moved to its raised position, locking means for interlocking with the control member for locking the same against turning the burner on, and means including a resilient member between the plunger and the last-named means for yieldingly moving the interlocking means into a position to lock the control means against turning the burner on, when the lid is being moved to its closed position.

8. In a stove, the combination of a burner, a movable lid mounted to close down over the burner, a movable control member for turning on the burner, a plunger engaging the lid in its closed position and capable of moving forward when the lid is raised, means for advancing the plunger when the lid is raised, a stop with automatic means for placing the stop back of the plunger when the plunger advances, said stop operating to prevent closing the lid; and yielding means for resisting movement imparted to the plunger by the closing lid.

9. In a stove, the combination of a burner, a movable lid mounted to close over the burner, a control member for turning the burner "off" or "on," a lock for the control member, yielding resistance means for resisting the closing of the cover, and means for inhibiting the operation of the resistance means when the control member is in its "off" position.

10. In a stove, the combination of a burner, a control member capable of assuming an "off" position and an "on" position for controlling the burner, a lock for the control member, a lid mounted to close down over the burner, a plunger, a spring for urging the same against the lid in its closed position and operating to advance the plunger when the lid is being raised, means connecting the plunger and the lock, operating to move the lock to release the control member near the end of the advancing movement of the plunger.

11. In a stove, the combination of a burner, a hinged lid mounted to close over the burner, a control member for turning the burner off or on, a lock for the control member to prevent operation of the same unless the lid has been raised, a movable contact member, resilient means for maintaining the same pressed against the lid while in its closed position, an actuating member

for the lock, said resilient means operating to advance the said contact member when the lid is raised, means connecting the contact member and the actuating member, a stop, and means controlled by the said actuating member for presenting the stop back in the path of the contact member to resist the closing of the lid.

12. In a stove, the combination of a burner, a hinged lid mounted to close over the burner, a control member for turning the burner off or on, a lock for the control member to prevent operation of the same unless the lid has been raised, a movable contact member, resilient means for maintaining the same pressed against the lid while in its closed position, an actuating member for the lock, said resilient means operating to advance the said contact member when the lid is raised, and means including a yielding part connecting the contact member to the lock and operating to pull the lock toward its locking position, if it is attempted to close the lid when the control member is in its "on" position.

13. In a stove, the combination of a burner, a movable lid mounted to close down over the burner, a movable control member for turning on the burner, yielding means capable of forcefully and yieldingly resisting the closing of the lid, and means, associated with the yielding means and with the control member and controlled by the position of the control member, to cause the yielding means to resist the closing of the lid if the control member is in the position that turns the burner on.

14. In a stove, the combination of a burner, a movable lid mounted to close down over the burner, a movable control member for turning on the burner, yielding means capable of forcefully and yieldingly resisting the closing of the lid, and means associated with the yielding means and with the control member controlled by the position of the control member for causing the yielding means to resist the closing of the lid when the control member is in the position that turns the burner on, and means associated with the yielding means for locking the control member against turning the burner on when the lid is in its closed position.

RICHARD BESOCKE.
